UNITED STATES PATENT OFFICE.

HEBER C. PETERS, OF BOSTON, MASSACHUSETTS, ASSIGNOR TO FRANK W. WHITCHIER, OF SAME PLACE, SANFORD CRANDON, OF MELROSE, AND HERBERT L. TURNER, OF MALDEN, MASSACHUSETTS.

DESIGN FOR A RUBBER HEEL.

SPECIFICATION forming part of Design No. 28,912, dated June 21, 1898.

Application filed May 23, 1898. Serial No. 681,511. Term of patent 14 years.

To all whom it may concern:

Be it known that I, HEBER C. PETERS, a citizen of the United States, residing at Boston, in the county of Suffolk and State of Massachusetts, have invented and produced a certain new and original Design for Rubber Heels, of which the following is a specification, reference being had therein to the accompanying drawings.

Figure 1 is a plan view of a rubber heel for boots and shoes, showing my new design. Fig. 2 is a sectional view taken on the line 2 2 of Fig. 1.

As shown in the drawings, the leading or material features of my design consist of a raised or prominent ridge or line 1, following

the edge contour of the heel, the central disk 2, with prominent margin 3, and the field 4, intermediate the said ridge 1 and the disk 2 and filled with lines of short or low pointed 20 projections, as 5 5.

Having described my invention, what I claim as new, and desire to secure by Letters Patent, is--

The design for a rubber heel, substantially 25 as herein shown and described.

In testimony whereof I affix my signature in presence of two witnesses.

HEBER C. PETERS.

Witnesses:

LEPINE HALL RICE,
HENRY S. McGOWN.
